ELECTRIC LAMP AND THE LIKE AND ITS MOUNTING AND ELECTRICAL CONNECTION

Filed April 21, 1933

INVENTOR:
HAROLD D. BLAKE,
BY Charles V. Tuller
HIS ATTORNEY.

UNITED STATES PATENT OFFICE

2,006,155

ELECTRIC LAMP AND THE LIKE AND ITS
MOUNTING AND ELECTRICAL CONNEC-
TIONHarold D. Blake, Cleveland Heights, Ohio, as-
signor to General Electric Company, a corpo-
ration of New York

Application April 21, 1933, Serial No. 667,223

8 Claims. (Cl. 176—32)

My invention relates to electric incandescent lamps, photoflash lamps, radio tubes, and other similar devices including an electric energy translation element in a glass bulb or envelope, and especially to the mounting of such devices and to their electrical connections.

At present, electric lamps and the like, including radio tubes, are commonly provided with holding bases into which the bulb end or "seal" portion is inserted and cemented; the base embodying terminals or contacts connected to the filament(s) or other translation element(s) within the bulb. Such bases and the sockets to receive them occupy more space than is sometimes desirable; and in the case of radio tubes, especially, they are rather complicated and expensive structures. Moreover, the cementing, baking, and soldering involved in "basing" a bulb make it a troublesome and costly operation.

I provide for the mounting and electrical connections of electric lamps and the like without necessity for bulky bases, as by means, such as securing and connective arms or wings, preferably embodied in comparatively thin, flat mounting and connective devices or "bases" affixed to the bulb end. Arranged to abut against the bulb end, as I prefer to apply it, such a flat disc-like structure can be secured thereto without the basing required in ordinary basing practice, by known methods of uniting to glass the materials suitable for such a structure,—including the use of various adhesives, as well as direct sealing of glass to certain metals or alloys by fusion or thermal softening of the glass. Such a mounting and connective device (especially when of suitable metal, such as an iron alloy containing about twenty-five per cent chromium and known commercially as "Allegheny 55") may even form the end wall of the bulb or envelope, in lieu of glass,—although in the present instance I have shown an envelope entirely walled with glass.

Various other features and advantages of my invention will appear from the following description of species thereof, and from the drawing.

In the drawing, Fig. 1 is a perspective view of a photoflash lamp having the "base" of my invention; Fig. 2 is a vertical section through a portion thereof; Fig. 3 is a similar section through a modification; Fig. 4 is a perspective view of a holding device or socket for the base shown in Figs. 1, 2, and 3; Fig. 5 is a perspective view of a portion of a lamp showing a modified base of my invention having three terminals; Fig. 6 is a perspective view of a radio tube having another species of the base of my invention; Fig. 7 is a side elevation

thereof, partially in section; Fig. 8 is a plan view of a holding device of socket for the radio tube base; and Fig. 9 is a section on an enlarged scale along line 9—9 of Fig. 8.

Figs. 1 and 2 show my invention applied to a photoflash lamp of the type disclosed in U. S. patent to Ostermeier Re. 18,678, reissued December 6, 1932, comprising a glass bulb 10 containing metal foil 11, and having an inward extending glass tube stem 12 of the so-called "tipless" variety. The stem 12 here illustrated is of the type disclosed in U. S. patent to Mitchell and White No. 1,423,956, granted July 25, 1922, having a flattened "press" portion 13 through which the current leads 14 and 15 are sealed, and also having an exhaust tube 16 inside the main stem tube 12, attached to the press 13 and opening therethrough at 17 into the interior of the bulb 10.

The exhaust tube 16 extends outward through the main stem tube 12 to the sealed end 18, which preferably projects from the end 18a of the bulb 10 as a stud or spur. (However, it is to be understood that such a projecting stud or spur on the end of the bulb 10 might be provided in some other way,—especially in the case of an old-fashioned bulb-tipped lamp,—or might even be dispensed with.) Preferably, the bulb end 18a (formed by the usual stem tube flange and the end of the bulb neck to which this flange is sealed in manufacture) is molded or otherwise shaped to a regular form such as best shown in Fig. 2, presenting a fairly flat end surface, square with the bulb axis and of substantial radial width. Against this end surface is seated my mounting and connective device 19, shown as a fairly stiff round disc of insulating material like fiber or high-grade cardboard, or Bristol board, with a snug-fitting center hole 20 for the stud 18. Openings 21 for the respective leads 14 and 15 are formed as slits extending out from the hole 20 about even with the inner wall of the stem tube 12. The disc 19 has diametrically opposite wings or arms 22, 23 projecting outward from its generally circular periphery beyond the periphery of the bulb end 18a, in line with the slits 21. The disc 19 may be fastened to the flat bulb end surface at 18a with any suitably strong adhesive or "glue" that sticks well to glass. In this particular instance a material manufactured by the General Electric Company under the trade name "Glyptal" and numbered 1276 is used. The leads 14 and 15 are passed through the disc opening 20 and drawn outward into the slits 21 when the disc 19 is ready to be applied; and after it has

been glued to the bulb end 18a, the leads are 55

drawn tight and bent to extend outward along the bottom surfaces of the wings 22, 23 to their ends, where they may be secured by doubling or hooking them around the wing ends in notches 24. 5 The notches 24 fit tightly with said wires and tend to retain them in place. The portions of the leads 14, 15 on the wings 22, 23 serve as lateral contacts for the device 19.

Fig. 3 shows a like application of a like disc 19 to a bulb end 18b of the more irregular shape produced by sealing a flared stem tube 12 into the bulb neck in the usual way, without any special shaping or molding of the bulb end. Although this irregular bulb end 18b is less slightly, 15 and affords very little flat area for the attachment of the disc 19, the result is still practically satisfactory,—at any rate if the annular bulb end lies all in one plane substantially square with the bulb axis.

20 Fig. 4 shows a holding device or "socket" for a lamp such as shown in Figs. 1-3. This socket device comprises an insulating base plate 25 (as of rubber) with a pivot hole or socket 26 to take the pivot stud 18, and with diametrically opposite spring clips 27, 28 to receive and hold (grip) the mounting wings 22, 23, and make electrical connection to the wing contacts. The lamp is mounted in this device by inserting its stud 18 in the hole 26 with the wings 22, 23 "indexed" to fall between the clips 27, 28, and then turning the lamp clockwise till the wings force apart the resiliently separable clip legs and enter between them. The upper clip legs have shoulders 29 to limit entry of the wings into the clips, and forward-bevelled latch-ends with rearward bevelled shoulders 30 to prevent the lamp wings 22, 23 from jarring out of the clips. Between the clips 27, 28 the base plate 25 has a diametral protuberance 31 to engage against the disc 19 and at least compensate for the thickness of the lower clip legs, so as to prevent the lamp from vibrating or oscillating in the socket device.

Fig. 5 shows my invention applied to a lamp or the like which may contain two filaments or translation elements. Accordingly, the disc 19a has three wings or arms 22, 23, and 32 corresponding to the three leads 14, 15 and 33. In this instance, the construction of Figs. 1-3 is supplemented with contact clamps or strips 34, extending across the wings 22, 23, 32 over their current leads 14, 15, 33, with the strip ends bent around under the wings, so as to grip and secure the leads. The clamps 34 serve as the lateral wing contacts. Except as otherwise indicated, the construction corresponds to that of Figs. 1 and 2. This lamp of Fig. 5 may be mounted in a socket device (not shown) similar to that of Fig. 4, but provided with another contact clip for the additional wing 32.

60 Figs. 6 and 7 show the application of my invention to a radio tube with six current leads 35 issuing from its stem tube 36,—and, incidentally, an additional lead 37 extending out through the top of the bulb and attached as usual to a cap 38. 65 The sealed bulb end 39 is shown molded (as in Figs. 1, 2 and 5) to afford a flat axially squared surface 40 for the attachment of the disc 41. This disc 41 has six wings or arms 42, a snug center hole for the projecting exhaust-tube stud or spur 43, and lead-wire slits 44 (one for each wing as in Figs. 1-3 and 5) to assure separation of the numerous leads within the stem tube 36 when drawn taut in the outer ends of the slits 44. The wings or arms 42 are preferably arranged in such unbalanced manner (or with such irregularities of

angular spacing) as to facilitate indexing: i. e., so that the tube can only be mounted in a support or socket in one angular relation thereto. Except as otherwise indicated, the construction of the device is like Figs. 1 and 2.

5 Figs. 8 and 9 illustrate a holding device or socket suitable for the tube of Figs. 6 and 7. Generally similar to the socket device of Fig. 4, that of Figs. 8 and 9 has in its insulating base plate 45 a socket hole 46 surrounded by six spring clips 47, suitably located. When too closely crowded together for clips such as 27, 28 in Fig. 4 to be feasible, these clips 47 may be of the more compact type shown in Fig. 9. This consists of a bent springy metal strip with a connector portion 48 extending down through a slot in the base to a conductor 49, and a horizontal contact portion 50 connected through a semi-circular portion 51 to another horizontal contact portion 52. The horizontal contact portion 52 is resiliently separable from the horizontal contact portion 50, by spring flexure of the semi-circular portion 51 to admit and grip a wing 42 between them. When all six wings are thus engaged and held, the resistance to disengagement is ample, even without anything like the shoulder 30 in Fig. 4; but a similar resistance to disengagement can be provided.

What I claim as new and desire to secure by Letters Patent of the United States, is:

1. An electric device comprising a bulb; a disc 30 having a plurality of apertures abutting against the bulb end and affixed thereto, with wing portions projecting outward beyond the bulb end periphery; and current leads issuing from the bulb end extending through different disc apertures and outward on the disc wings, with lateral contacts on said wings connected to said leads.

2. An electric device comprising a bulb with an exhaust tube projecting from its end and leads sealed in said end; and an apertured disc affixed 40 to said bulb end around said exhaust tube and affording wings which project outward beyond the bulb end periphery and have lateral contacts connected to the said leads.

3. An electric device comprising a bulb with a 45 stud projecting from its end; an apertured disc affixed to said bulb end around said stud and slotted outward from its aperture, and also having wings which project outward beyond the bulb-end periphery; and current leads issuing 50 from the bulb end extending through the disc slits and outward on said wings, and secured to the latter to serve as lateral contacts.

4. An electric device comprising a bulb with a stud projecting from its end; an apertured disc 55 affixed to said bulb end around said stud affording end-notched wings which project outward beyond the bulb-end periphery; and current leads issuing from the bulb end extending outward to the end notches of said wings, and hooked into 60 said notches.

5. The combination of an electric device comprising a bulb with wings on its end projecting outward from the bulb end periphery, a stud projecting from said bulb end and centrally located 65 with respect to said wings, and lateral contacts on said wings, and a holder having a pivot hole for said stud, and contact clips for holding said wings and making electrical connection to their said contacts, said wings being engageable with 70 said clips by turning the said device on said stud as a pivot in said hole.

6. An electric device of the class described comprising a bulb having leads sealed in an end wall thereof, a disc of insulating material abutting 75

against the said end of said bulb and affixed thereto, said disc having integral wing portions projecting outward beyond the bulb end periphery, and contacts on said wings connected to said leads.

7. An electric device of the class described comprising a bulb having leads sealed in an end wall thereof, a disc of insulating material abutting against the said end of said bulb and affixed thereto, said disc having integral wing portions projecting outward beyond the bulb end periphery, and said leads extending outward on said

wing portions and secured thereto to serve as contacts.

8. An electric device of the class described comprising a bulb having leads sealed in an end wall thereof and a stud projecting from said end, an apertured disc of insulating material abutting against the said end of said bulb and affixed thereto around said stud, said disc having integral wing portions projecting outward beyond the bulb end periphery, and contacts on said wings connected to said leads. 5

HAROLD D. BLAKE.
